UNITED STATES PATENT OFFICE.

EDWARD A. HOFF, OF MILWAUKEE, WISCONSIN.

ROCK-CRUSHER.

No. 857,940.

Specification of Letters Patent.

Patented June 25, 1907.

Application filed June 13, 1906. Serial No. 321,484.

To all whom it may concern:

Be it known that I, EDWARD A. HOFF, residing in Milwaukee, in the county of Milwaukee and State of Wisconsin, have invented new and useful Improvements in Rock-Crushers, of which the following is a description, reference being had to the accompanying drawings, which are a part of this specification.

10 This invention has for its object to provide a rock crusher of the gyratory type with operating means which will greatly reduce the friction and wear of the parts and thereby increase the efficiency and durability of the 15 rock crusher.

Another object of this invention is to accomplish the above purpose by means of cam operated toggles for producing the gyratory motion of the main shaft and head.

20 With the above and other objects in view the invention consists in the rock crusher herein claimed, its parts and combinations of parts and all equivalents.

Referring to the accompanying drawings 25 in which like characters of reference indicate the same parts in the several views:—

Figure 1 is a central sectional view of a rock crusher constructed in accordance with this invention; Fig. 2 is a sectional plan view 30 thereof on the plane of line 2—2 of Fig. 1; and, Fig. 3 is a sectional elevation of one of the intermediate joints of the toggle connections, showing the caster roller.

In these drawings 5 represents the lower 35 shell and 6 the top shell secured together and provided with the concave 7 and the hopper 8 as usual, there being spider arms 9 extending across the mouth of the hopper and supporting a suspension bearing 10. A main 40 shaft 11 is pivotally suspended in the suspension bearing 10 in the ordinary manner and has secured to it a head 12 to coöperate with the concave 7 in crushing the rock during the gyratory motions of the main shaft 11, 45 the rock being fed to these coöperating parts by the hopper 8 and being discharged therefrom by the inclined partition 13 and chute 14. All of the construction thus far described is well known and constitutes no 50 part of this invention, except in combination with the novel operating means for the main shaft to be described.

With rock crushers of this type it has been the practice to produce the gyratory motions 55 of the main shaft by means of an eccentric turning on the lower end thereof and riding

in a fixed bearing. This form of operating means imposes a considerable amount of resistance to the driving of the main shaft and is subject to severe wear, making it necessary to frequently replace the wearing parts with great inconvenience and loss of time. The present invention is designed to dispense entirely with the eccentric operating means and provide toggles connecting the 65 main shaft with the lower shell and caused to swing the main shaft by having their intermediate connections forced upwardly by means of a rotary cam bearing on casters carried by said intermediate connections of 70 the toggles.

The main shaft 11 at its lower end is provided with a pair of flanges 15 between which are pivotally mounted blocks 16 having toggle links 17 pivotally connected to their sides. 75 Each pair of toggle links 17 embraces a yoke 18, being loosely mounted on trunnions 19 at the ends thereof. Toggle links 20 are also loosely mounted on the trunnions 19 of the yokes 18 and those of each pair are pivotally 80 connected to the opposite ends of blocks 21 which are pivotally mounted in brackets 22 clamped to the lower shell by having stems passing therethrough with jam nuts on the outside. The blocks 16 and 21 are so mounted 85 as to permit of a lateral swing of the toggles formed by the toggle links 17 and 20 with their intermediate connections, as shown by the upper and lower toggles in Fig. 2.

90 Each of the yokes 18 has a caster 23 swiveled therein with a grooved roller 24 to ride on a cam flange 25 which is carried by a beveled gear 26 journaled in the bottom plate 27, said beveled gear being mounted upon 95 antifriction rollers 28 journaled in the bottom plate and riding on a depending annular flange 29 of the gear. The beveled gear is preferably journaled in the bottom plate by having a stud 30 projecting downwardly 100 therefrom and turning in a cup-shaped bearing 31 in the bottom plate, there being an oil recess 32 provided in said bearing beneath the stud. The cam 25 is slightly eccentric to the beveled gear 26 in order that it may pass 105 directly beneath the caster rollers 24 in the different positions of the toggles, and the caster rollers are swiveled to enable them to keep their engagement with the cam flange 25 at all times without binding.

110 A counter shaft 33, which is connected with some suitable source of power, enters

the lower shell 5 and has a beveled pinion 34 on its end meshing with the beveled gear 26, and by this means the beveled gear is caused to rotate in its bearing 31 and upon its frictionless support formed by the bearing rollers 28.

In operation, the turning of the beveled gear 26 by means of the counter shaft causes the cam flange 25 to turn and ride beneath the caster rollers 24 of the toggles and cause them to successively straighten out, as shown at the left of Fig. 1, to force the end of the main shaft 11 therefrom. The pitch of the cam is such that two opposite toggles are in their opposite extreme positions at the same time while the other two are in intermediate positions, the position of the main shaft causing them to swing away from the straightened toggle as shown in Fig. 2. As this straightening and relaxing of the toggles is produced in rotation, the lower end of the main shaft is caused to gyrate and produce the crushing of the rock between the head 12 and the concave 7.

With this construction there is very little loss due to friction, as the cam acts as a wedge working between two sets of friction rollers, the bearing rollers 28 and the caster rollers 24, and frictional engaging surface is reduced to a minimum.

Furthermore, the reaction of the thrust upon the lower end of the main shaft 11 is divided between the heavy walls of the lower shell 11 and the bottom plate 27 instead of being entirely upon the latter, as is usually the case where eccentric means are employed for producing the gyratory motions.

Another feature of advantage of this invention is the facility with which parts may be replaced or repaired when they become worn or broken, it being only necessary to remove the bottom plate 27 with the beveled gear 26 and all of the parts become freely accessible.

What I claim as my invention is;

1. Means for producing a gyratory motion, comprising a pivotally mounted shaft, a series of toggles connected with the shaft, a stationary support to which the toggles are connected, and means for moving the toggles successively for causing them to exert pressure upon the shaft in different directions.

2. Means for producing a gyratory motion, comprising a pivotally mounted shaft, toggles connected with the shaft and extending in different directions, a stationary support to which the toggles are connected, and a rotatable cam bearing on the toggles and causing them to straighten successively to exert pressure upon the shaft.

3. Means for producing a gyratory motion, comprising a pivotally mounted shaft, toggles connected to the shaft and extending in different directions, a stationary support to which the toggles are connected, grooved

rollers carried by the intermediate joints of the toggles, and a rotatable cam bearing on the rollers for causing the toggles to be straightened successively to exert pressure upon the shaft.

4. Means for producing a gyratory motion, comprising a pivotally mounted shaft, a series of toggles swivelly connected therewith and extending in different directions, a stationary support to which the toggles are pivotally connected, grooved caster rollers swivelly mounted at the intermediate joints of the toggles, a rotatable cam bearing on the caster rollers and adapted to force the toggles to straighten successively and exert pressure upon the shaft.

5. A rock crusher, comprising a concave, a pivotally mounted main shaft, a head carried by the main shaft to coöperate with the concave, and means for gyrating the main shaft, comprising a series of toggles connected with the main shaft, a stationary support to which the toggles are connected, and means for moving the toggles successively for causing them to exert pressure upon the shaft in different directions.

6. A rock crusher, comprising a concave, a pivotally mounted main shaft, a head carried by the main shaft to coöperate with the concave, and means for gyrating the main shaft, comprising toggles connected with the shaft and extending in different directions, a stationary support to which the toggles are connected, and a rotatable cam bearing on the toggles and causing them to straighten successively to exert pressure upon the shaft.

7. A rock crusher, comprising a concave, a pivotally mounted main shaft, a head carried by the main shaft to coöperate with the concave, and means for gyrating the main shaft, comprising toggles connected to the shaft and extending in different directions, a stationary support to which the toggles are connected, grooved rollers carried by the intermediate joints of the toggles, and a rotatable cam bearing on the rollers for causing the toggles to be straightened successively to exert pressure upon the shaft.

8. A rock crusher, comprising a concave, a pivotally mounted main shaft, a head carried by the main shaft to coöperate with the concave, and means for gyrating the main shaft, comprising a series of toggles pivotally connected therewith and extending in different directions, a stationary support to which the toggles are pivotally connected, grooved caster rollers swivelly mounted at the intermediate joints of the toggles, and a rotatable cam bearing on the caster rollers and adapted to force the toggles to straighten successively and exert pressure upon the shaft.

9. A rock crusher, comprising a concave, a pivotally mounted main shaft, a head carried by the main shaft to coöperate with the con-

cave, and means for gyrating the main shaft, comprising a series of toggles pivotally connected therewith and extending in different directions, a stationary support to which the 5 toggles are pivotally connected, grooved caster rollers swivelly mounted at the intermediate joints of the toggles, a rotatable cam means bearing on the caster rollers and adapted to force the toggles to straighten 10 successively and exert pressure upon the shaft, and friction rollers on which the cam means bears.

10. A rock crusher, comprising a shell, a concave carried thereby, a pivotally mounted main shaft, a head on the main shaft co-operating with the concave, and means for gyrating the main shaft, comprising toggles pivotally connected with the main shaft and with the shell, caster rollers carried by the 15 toggles at their intermediate connections, a beveled gear journaled in the shell, a cam flange thereon bearing against the caster rollers, friction rollers in the shell upon which the beveled gear bears, and a counter shaft 20 entering the shell and having a pinion meshing with the beveled gear.

25 11. In a rock crusher, a shell, a concave carried thereby, a pivotally suspended main shaft, a head carried thereon co-operating

with the concave, and means for gyrating the 30 main shaft, comprising a pair of annular flanges on the main shaft, blocks pivotally mounted therebetween, pairs of toggle links pivotally connected to the blocks, yokes having trunnions on which the pairs of toggle 35 links are loosely mounted, brackets connected to the shell, blocks pivotally mounted in the brackets, pairs of toggle links connecting the last mentioned blocks with the trunnions of the yokes, grooved caster rollers swiveled 40 in the yokes, a bottom plate on the shell, a beveled gear journaled therein, a cam flange on the beveled gear bearing on the caster rollers, bearing rollers journaled in the bottom plate, a flange on the beveled gear riding 45 on the bearing rollers, and a counter shaft entering the shell and having a beveled pinion meshing with the beveled gear for turning the beveled gear and causing the cam flange to force the toggles formed by the sets 50 of toggle links so as to exert pressure upon the main shaft.

In testimony whereof, I affix my signature, in presence of two witnesses.

EDWARD A. HOFF.
